UNITED STATES PATENT OFFICE.

GEORGE WEISS, OF CHICAGO, ILLINOIS.

VENDING MACHINE.

Application filed November 18, 1920. Serial No. 424,873.

To all whom it may concern:

Be it known that I, GEORGE WEISS, a citizen of the United States, residing at Chicago, in the county of Cook and State of Illinois, have invented certain new and useful Improvements in Vending Machines, of which the following is a specification.

My invention relates to improvements in vending machines and has particular reference to a machine for vending automatically comparatively bulky articles, such as sanitary napkins.

Among the salient objects of my invention are to provide an improved machine for vending bulky articles and which will occupy a minimum of wall space; to provide an improved machine so organized that the article is forcibly propelled therefrom by manually-applied power; to provide an improved construction in which the possibility of fraudulently removing articles therefrom is reduced to a minimum; to provide a vending machine which shall be simple and inexpensive to design and manufacture, and which will not readily break down or get out of adjustment; and, in general, to provide an improved vending machine of the character referred to.

In the drawings, which illustrate one application of my invention to a machine of the specific character heretofore referred to,—

Fig. 1 is a front elevation of the machine; Fig. 2 is a side elevation of said machine, certain parts being removed for the sake of clearness;

Fig. 3 is a section taken on the line 3—3 of Fig. 1;

Fig. 4 is a section taken on the line 4—4 of Fig. 2;

Fig. 5 is a section taken on the line 5—5 of Fig. 4;

Fig. 6 is a side elevation of the lower portion of the machine shown in Fig. 1; and

Fig. 7 is a section taken on the line 7—7 of Fig. 2.

Referring to the drawings, it will be seen that the articles of merchandise are arranged in a stack within a vertically upstanding rectangular article-chute 11, said article-chute 11 being equipped with a cover 12 hinged as at 13 to the front of the article-chute 11. The rear of the cover plate 12 is fitted with a suitable hasp arrangement 14 for the purpose of accom-

modating a padlock whereby the cover may be securely locked in place. It will be understood that the cover 12 is removed by the service man for the purpose of replenishing the stock of merchandise whenever he makes his rounds to collect the coins deposited.

The article-chute 11 is rigidly united to the upper end of the frame or mechanism housing, which frame may be constructed of suitable castings or stampings, or a combination thereof, as preferred. Referring to Figs. 2 and 3, it will be noted that the front wall 15 of the article-chute extends considerably lower down than the rear wall 16 of said chute. The bottom plate or floor 17 of said chute being inclined, the articles 10 will assume an oblique or inclined position, as indicated, so that when the bottom article is discharged from the chute through the curved mouth opening, said article will not be delivered horizontally but at rather an abrupt angle, which direction will be converted into a still more vertical position, as indicated at 19, by reason of the curved skirt 20 extending down below the bottom of the article-chute. A suitable inclined seat 21 with a bottom lip or flange 22 is provided to receive the article upon discharge, thereby preventing it from falling to the ground.

In order to simplify the mechanism as much as possible, I prefer not to equip the machine with any special mechanism which will return the coin to the customer when the machine is empty. In place of such mechanism, the lower portion of the front wall of the chute is apertured and fitted with a glazing, as shown at 23 in Fig. 1. This enables the customer to see at a glance whether or not the machine is charged.

In the preferred embodiment herein disclosed, the discharging or propelling mechanism comprises means equipped for unidirectional movement, said means taking the form of a pair of endless chains located just below parallel slots in the inclined floor 17 of the article-chute. Said chains are trained around idler sprocket wheels 24 keyed on a transverse horizontal shaft 25 and a pair of driving sprocket wheels 26 keyed on another transverse horizontal shaft 27 parallel with the shaft 25. Both of said shafts 25 and 27 are journaled in suitable bearings, as 28, provided in the frame of the machine and are positioned

endwise by means of suitable collars, as 29. The chains 30 do not quite touch the under side of the bottom article, so that said chains may be advanced without disturbing or injuring the exterior of the package. The packages are actually propelled or discharged out of the opening 18 by small pushers or drags 31 located at equi-spaced intervals in the length of the chains 30, the arrangement being such that an operative movement of the propelling mechanism results in advancing the chain a distance equal to the spacing between flights or pushers. In the present instance, the length of the chain is equal to twice the circumference of the driving sprocket 26, and there are two sets of flights, so that a single complete revolution of the shaft 27 will move the chain the required distance. It will be manifest that the number of flights is a matter of choice, two sets being herein described for the sake of illustration. A plate 31^a prevents sagging of the chains.

The inclination of the bottom wall 17 of the article-chute is such that there will be no tendency for the articles to slide out of the chute, and the weight of the stack will maintain the lowermost article in flat fitting engagement with the floor 17. If desired, a weight 32 may be placed on the top of the stack in order to cause the column of articles to descend with substantial uniformity, said weight having side flanges 32^a constituting stops for limiting the descent of the weight and thereby preventing contact with the chain flights when the machine is empty.

The shaft 27 is actuated by a train of manually-operable gearing 33 in which the coin itself functions as an essential link or connection. The gear 33, which is pinned or keyed to the driving sprocket shaft 27, is driven through an intermediate or idler gear 34 on shaft 35 by a large spur gear 36. Said driving spur gear 36 is keyed to the inner end of a sleeve or quill 37, said quill being journaled in a fixed bearing 38 formed as a part of one of the frame castings. On the outer end of said sleeve 37 there is keyed a drum 39, the hubs of said gear 36 and drum 39 accurately positioning the sleeve 37 as to longitudinal movement.

On the hub of the drum 39 and preferably fixed to one side thereof there is keyed a ratchet wheel 40, the teeth 41 of which operate with a pawl 42 pivotally mounted on a pin 43 fixed in the frame casting 44, the arrangement being such that backward movement of the chains or belts 30 and associated gearing is prohibited.

The drum 39 is made with a circumferential flange 45, continuous, except for a set of four slots registering with and permitting entrance to a set of four coin-pockets or slots 46 in the arms or enlargements 47 of

the drum. When in idle or non-operative position, the drum 39 is positioned with the entrance to one of the coin-pockets 46 in register with the discharge opening of the coin-chute 48. Said coin-chute 48 is, in the present instance, for the sake of simplicity, illustrated as a simple curved tube of sufficient area to admit a nickel or other coin by which the machine is intended to be operated. It should be understood, however, that in practice it may be desirable to use a chute suitably organized to discard improper coins or slugs. Said chutes are well-known in the art and need not be specifically described.

The said drum 39 and sleeve 37 are actuated (when a coin is inserted) by a crank-handle 49 outside and to the right of the machine, and keyed to the outer end of a transverse horizontal shaft 50. Said shaft 50 extends centrally through the sleeve 37 and is journaled at its left-hand end in a bearing 51 and at its right-hand end in a bearing 52 which is formed as a part of the exterior frame part 53, there being sufficient space between the frames 44 and 53 to accommodate the engaging mechanism. On the shaft 50 and against the inner face of the bearing 52 there is keyed an operating segment 54 circumferentially flanged as at 54^a at its outer edge, the flange being of the same radius from the center of the shaft 50 as the flange 45 of the drum 39. A torsion spring 55 surrounding the left-hand portion of the shaft 50 serves to maintain the handle 49 in upright position against the stop-lug 56, as shown in Fig. 6. One end of said spring 55 is positioned in the frame of the machine and the other end is secured in an adjustable collar 57, whereby the tension of the spring 55 may be conveniently adjusted. The sweep of said crank 49 is limited to ninety degrees by another stop-lug 58.

The drum 39 and the segment 54 substantially abut one against the other, but same are normally disconnected by reason of the fact that the sleeve 37 is not keyed to the shaft 50, so that the shaft 50 may be operated by the crank 49, without affecting the drum 39. In order to operate the drum by the handle when the coin is inserted in the chute, the segment 54 is equipped with a slot 59 similar to one of the slots 46 and registering therewith and with the bottom end of the chute 48 when the handle 49 is in upright position against the stop 56. In order to improve mechanical characteristics of the design, the slot 59 may be of less width than the slot 46, but the aggregate width of said slot portions is such that when in register with each other they form a radial pocket of necessary cross-section and area to admit the coin 60. The coin 60 thus functions as a clutch or connection between the segment and the drum.

A guard member 61 compels the coin to remain in the pocket during a complete ninety-degree operative movement of the handle 49 in the direction of the arrow 62, and thus prevents it from being prematurely discharged. As soon as the coin-pocket has passed by the end 63 of said guard, that is to say, when the handle is brought down on the stop 58, there is nothing to prevent the coin from sliding out of the coin-pocket, and it drops down into the money box 64, thus freeing the segment 54 from the drum 39 and permitting the spring 55 to return the segment 54 with its slot 59 lined up with another slot 46, and handle 49 to its upright position. Said money box 64 is pivoted on a fixed shaft or pin 65 and is maintained in the position shown by means of a shaft 66 extending through the box 64 and suitable bosses 67 and 68 on lower portions of the frame members 44 and 53. The shaft or lock-pin 66 has a head 69 on one end, and on the other end is apertured, as shown at 70 to enable the application of a padlock or other seal. The ratchet wheel 40 serves prevent backward movement of the mechanism after a coin has been inserted and compels the customer to effect a complete ninety-degree movement of the handle before it is possible to move the handle back into its original upright position. In order to position the drum 39 normally with the slot opening in accurate register with the discharging opening of the coin-chute 48, I prefer to use a special registering device. Said device comprises a plunger 71 contained in a cylindrical recess 72, the axis of which is parallel with the axis of the shaft 50. The left-hand end of said recess is open and the right-hand end is drilled out to accommodate the tail of said plunger 71, the head 73 of said plunger sliding in the main recess, which accommodates the coil compression spring 74. Said compression spring 74 forces the conical head 73 of the plunger towards the gear 36, in the side of which there is formed a set of four equi-spaced registering conical depressions or countersinks 75 designed to fit the conical end 73 of the plunger. It will be manifest that any tendency towards improper register will be corrected by reason of the plunger 73 cooperating with the counter-sinks 75 in a well known manner.

I provide special means for locking the chains or belts against movement when the machine is at rest and in the absence of an inserted coin. Said means comprises a gravity-actuated dog 76 (see Fig. 4) pivoted in an opening of the frame member 44 on a fixed pin 77 at right-angles to, and above, the shaft 50. The position of said dog 76, due to the superior weight of the counter-balancing tail 78, is normally, in

the absence of a coin, according to the dotted line position 79 with the point of the dog extending through an aperture communicating with the coin-pocket in the drum 39, so that said dog serves to lock the drum in normal position. When the coin is inserted, as shown in Fig. 4, the weight of the coin forces the dog into the full line position, as indicated, and the circumferentially-extending opening 80 allows the drum to be rotated without engaging said dog.

The details of construction and operation herein described are merely illustrative of a single application of my invention, the scope of which should be determined by reference to the appended claims, said claims being construed as broadly as possible consistent with the state of the art.

I claim as my invention:

1. In a vending machine, the combination of a propeller for discharging an article, means for actuating said propeller, said means being normally disconnected therefrom and adapted to drive said propeller through a coin which when inserted constitutes a link in the train of operating mechanism of said means, said means including relatively movable independent parts having co-acting recesses forming a coin-receiving pocket, one part having an opening, and a dog pivotally mounted to normally extend into the opening to prevent movement of the part provided with the opening, and adapted upon insertion of the coin in the pocket to be displaced from the opening to permit said parts to turn in unison for actuating the propeller.

2. In a vending machine, the combination of a propeller for discharging an article, means for actuating said propeller, said means being normally disconnected therefrom and adapted to drive said propeller through a coin which when inserted constitutes a link in the train of operating mechanism of said means, said means including relatively movable independent parts having co-acting recesses forming a coin-receiving pocket, one part having an opening, and a dog pivotally mounted to normally extend into the opening to prevent movement of the part provided with the opening, and adapted upon insertion of the coin in the pocket to be displaced from the opening to permit said parts to turn in unison for actuating the propeller, the coin being released by gravity upon inverting the pocket at the limit of its movement and the dog having a weighted end adapted to cause the opposite end thereof to engage in a corresponding opening to hold the part provided therewith against movement.

3. In a vending machine, the combination with a propeller for discharging articles, means geared thereto for actuating the

85

100

105

110

115

120

125

130

same, a pair of rotatable parts mounted on a common axis and having co-acting recesses forming the coin-receiving slot, a dog pivoted on a fixed axis and normally extending through an aperture in one of said parts to hold the same and the propeller against movement, said means being displaced by the weight of a coin in the slot to permit said parts to be turned at which time the 10 coin forms a connector between the parts whereby the propeller may be actuated.

4. In a vending machine, the combination with a propeller for discharging articles, means geared thereto for actuating the same, 15 a pair of rotatable parts mounted on a common axis, one part being rigidly connected with the actuating means and having a recess therein, the other part having a plurality of equi-distantly spaced recesses 20 adapted each at times to register with the recess in the other part and having openings in its walls communicating with each of the recesses therein, and means carried by a stationary part of the machine to hold the 25 last-named part and the propeller against movement in the absence of an inserted coin in the pocket, said means adapted to extend through one of said openings and to be displaced therefrom by the coin.

5. In a vending machine, the combination with a propeller for discharging articles, means geared thereto for actuating the same, 30 a pair of rotatable parts mounted on a common axis, one part being rigidly connected with the actuating means and having a recess therein, the other part having a plurality of equi-distantly spaced recesses 35 adapted each at times to register with the recess in the other part and having openings 40 in its wall communicating with each of the recesses therein, a locking member carried by a stationary part of the machine and normally extending through one of said openings into the coin slot to hold said parts 45 and propeller locked against movement in either direction but adapted to be disengaged from the opening free of the part provided with the openings when the coin is inserted to connect said parts and permit the same to 50 be turned as one for operating the propeller through the geared connection, and means associated with said stationary part of the machine and a gear for positioning a recess in coin-receiving position and its opening 55 for engagement by the locking member.

6. In a vending machine, the combination 60 of a propeller for discharging an article, a manually operable member for actuating said propeller, geared connections between said member and said propeller, the member being normally disconnected from the propeller and adapted to drive the same through a coin which when inserted constitutes a link in the train of operating 65 mechanism, and means co-operating with

the coin-receiving part to restrain the same, the gear and the propeller against movement in either direction and released automatically when a coin is deposited for operatively connecting the member and propeller 70 through the gear.

7. In a vending machine, the combination of a propeller for discharging an article, a manually operable member for actuating said propeller, geared connections between 75 said member and said propeller, the member being normally disconnected from the propeller and adapted to drive the same through a coin which when inserted constitutes a link in the train of operating mechanism, and means for locking the propeller against movement in either direction, said means being released by the depositing of a coin.

8. In a vending machine, the combination of a rotary uni-directional propelling member, a pusher actuated by said rotary member for engaging an article to be discharged, a handle, means respectively associated with the handle and the propelling member constituting a driving connection and adapted to be made effective by the insertion of a coin, and means normally locking the propeller and associated parts against movement in either direction, said locking means being released by the weight of the coin upon insertion thereof.

9. In a vending machine, the combination of a rotary uni-directional propelling member, a pusher actuated by said rotary member for engaging an article to be discharged, a handle, means respectively associated with the handle and the propelling member constituting a driving connection and adapted to be made effective by the insertion of a coin, means normally locking the propeller against movement in either direction, additional means for preventing a backward movement of said propeller during the period of engagement between the handle and the propeller, said driving connection including a part normally free of rotation of the handle and another part fixed to rotate therewith, the latter part being normally returned to receiving position with the handle upon discharge of the coin, and means between a stationary part of the machine and a part of the driving connection to position the propeller and coin-receiving part free of the handle after 105 operative movements thereof.

10. In a vending machine, a frame, a shaft journaled in the frame, a segment fixed on the shaft, a coin chute, a drum having equi-distantly spaced coin-receiving 110 pockets, a sleeve loose on the shaft journaled on the frame and keyed to the drum, a propeller for discharging an article to be vended, and a gear chain between the sleeve 115 and propeller.

11. In a vending machine, a frame, a shaft journaled in the frame, a segment fixed on the shaft, a coin chute, a drum having equi-distantly spaced coin-receiving pockets, a sleeve loose on the shaft journaled on the frame and keyed to the drum, a propeller for discharging an article to be vended, a gear chain between the sleeve and propeller, means for locating the 5 pockets of the drum successively in receiving position, and means between the frame and drum adjacent each pocket for automatically holding the drum, gear chain and propeller against movement in either 10 direction when the pockets are empty, said means being automatically released when a coin is disposed in a pocket.
12. In a vending machine, a frame, a shaft journaled in the frame, a segment 20 fixed on the shaft, a coin chute, a drum having equi-distantly spaced coin-receiving pockets, a sleeve loose on the shaft journaled on the frame and keyed to the drum, a propeller for discharging an article to be vended, a gear chain for driving 25 the propeller and including a gear fixed on the sleeve and having depressions therein, and spring-pressed plungers carried by the frame and engaging the depressions, an operative movement of the gear chain being sufficient to move the propeller a distance to discharge an article to be dispensed and to hold another article in discharging position. 30
13. In a vending machine, a frame, a shaft journaled in the frame, a segment fixed on the shaft, a coin chute, a drum having equi-distantly spaced coin-receiving pockets, a sleeve loose on the shaft journaled on the frame and keyed to the 40 drum, a propeller for discharging an article to be vended, a gear chain between the sleeve and propeller for driving the latter and including a gear keyed on the sleeve, a gear on the propeller, and an idler gear 45 meshing with both, a handle for turning the shaft and drum through the medium of the segment, means to limit the movement of the handle in opposite directions, and means to return the same to normal 50 position.

GEORGE WEISS.
